GUM BALL DISPENSING MACHINE

Sidney A. Tarrson, Chicago, Ill., assignor to The Tarrson Company, Chicago, Ill., a corporation of Illinois

Application August 2, 1949, Serial No. 4,253

Term of patent 14 years

(Cl. D52—3)

To all whom it may concern:

Be it known that I, Sidney A. Tarrson, a citizen of the United States, residing at Chicago, in the county of Cook and State of Illinois, have invented a new, original, and ornamental Design for a Gum Ball Dispensing Machine, of which the following is a specification, reference being had to the accompanying drawing, forming a part thereof.

Fig. 1 is a perspective view of a gum ball dispensing machine embodying my new design; and

Fig. 2 is a top plan view thereof.

The essential features of my design reside in the portion shown in full lines.

I claim:

The ornamental design for a gum ball dispensing machine, substantially as shown and described.

SIDNEY A. TARRSON.
